UNITED STATES PATENT OFFICE

2,506,373

HOLDER FOR COLD CHISELS AND THE LIKE

Guy Willas McClain, Detroit, Mich.

Application November 1, 1946, Serial No. 707,218

2 Claims. (Cl. 81—1)

1

This invention relates to hand tools, and has particular reference to a tool for supporting a cold chisel, granite chisel, star drill, center punch, or like tools during a work operation.

An object of the invention is to provide a handle whereby hand tools of the character indicated above may be supported and struck with a hammer without danger of injuring the mechanic's hand.

Another object of the invention is the provision of a device of the character indicated which is constructed and arranged in such manner that a cold chisel or the like may be firmly gripped and held in operating position with greater efficiency.

Another object of the invention is the provision of a device of the character indicated which makes possible the holding of a cold chisel or similar tool in different angular positions with greater ease than is possible when the same tool is held directly in the palm of the hand.

The foregoing and other objects and advantages of the invention will become more apparent as the description proceeds, reference being made from time to time to the accompanying drawings, forming part of the within disclosure, in which drawings:

Fig. 1 is a side elevational view of a device embodying the invention.

Fig. 2 is a view similar to Fig. 1 with parts in section to illustrate the position of other parts.

Referring now more particularly to the drawings, it will be understood that in the embodiment herein disclosed, the device consists of a comparatively long shank 7 which is provided with a grip 8, preferably made of rubber or other flexible material, which is press-fitted or molded thereon to provide a shock absorbing hand grip. The shank 7 is preferably formed with a round cross section, but is provided with a large octagonal shaped portion 9, which is adapted to accommodate a wrench, whereby the shank 7 may be rotated as hereinafter described. The shank 7 is threaded, as at 10, to accommodate the end member 11, which is internally threaded, as at 12. The end member 11 is provided with a longitudinal bore 13 adapted to accommodate the cylindrical end 14 of a floating jaw 15, which is positioned in the transverse opening 16 formed in the circular head 17 of the member 11. The inner peripheral wall 18 of the head member 17 is serrated to match corresponding serrations formed on the end of the floating jaw 15, whereby the cold chisel or other tool may be gripped therebetween.

A jam nut 19 is carried on the threads 10, and is adapted to be moved into locking position 55

2

against the end of the member 11 to prevent the rotation thereof when the device is in operation.

In order to use the device, the jam nut 19 is rotated away from the end of the member 11, so that the shank 7 and member 11 are free to rotate with respect to one another.

The members 7 and 11 are then rotated with respect to one another so that the floating jaw 15 may recede to provide a sufficient clearance

10 for the introduction of the cold chisel or other tool into the opening 16. After the tool has been inserted into the opening 16, the shank 7 is preferably rotated with respect to the member 11, so that the end of the shank 7 abuts the member 14 to outwardly move the floating jaw 15 into locking engagement with the cold chisel or other tool to be held.

When sufficient pressure is exerted by the floating jaw 15 on the tool to be held, the jam nut 19 is moved into position against the end of the member 11 and the device is ready for operation.

Having described my invention, what I claim and desire to secure by Letters Patent is:

1. In a device of the character described, the combination of a substantially long shank having a shock absorbing hand grip thereon, means to rotate said shank, threads on said shank extending from said last named means to the end of said shank, an end member having a heavy walled circular head with a large transverse opening therein, a threaded longitudinal bore in said end member engaging the threads of said shank, a jamb nut on the threads of said shank and contacting the end of said end member, and a floating jaw in the transverse opening of said end member and having an extension in contact with the end of said shank.
2. The combination defined in claim 1, in which said floating jaw has a serrated arcuate edge oppositely disposed to a serrated edge formed on the wall of the said circular head.

GUY WILLAS MCCLAIN.
